UNITED STATES PATENT OFFICE.

JOHN ISAAC THORNYCROFT, OF BEMBRIDGE, ISLE OF WIGHT, ENGLAND.

JUICE-EXTRACTION APPARATUS.

1,409,797.

Specification of Letters Patent. Patented Mar. 14, 1922.

Application filed July 1, 1918. Serial No. 242,735.

To all whom it may concern:

Be it known that I, Sir JOHN ISAAC THORNYCROFT, F. R. S., a subject of the King of Great Britain and Ireland, residing at Bembridge, in the Isle of Wight, England, have invented Improvements in or Relating to the Juice-Extraction Apparatus, of which the following is a specification.

This invention relates to the extraction of juice from vegetable substances, and more particularly to the separation of juice containing sugar from comparatively soft vegetable substances such as beet, and the invention has for its object to simplify the construction of such juice-extracting plant, and correspondingly to reduce the cost both of its production and its operation, with the result that the production of sugar, for example, can be profitably carried out on a smaller scale than can be done with advantage by means of the apparatus, commonly used.

For this purpose, beet or other vegetable substance from which juice is to be extracted, is introduced into a vessel (hereinafter termed the diffuser), and moved therein against the force of gravity, being meanwhile subjected to the action of a solvent such as water, so that the solvent and juice will naturally flow in the opposite direction to the more solid vegetable substance and the portion of the descending stream richest in dissolved sugar or other matter, being denser, will tend to descend faster than the more watery portion, thereby enhancing the efficiency of the treatment, hereinafter termed "diffusion."

The material to be treated is forced into the lower part of the diffuser, which is preferably vertical, by means of a piston moved in a cylinder by suitable means, as for example, by a hydraulic ram, each stroke of the piston causing the material in the diffuser to rise, and ultimately to be discharged in a spent or nearly spent condition at the top of the diffuser, whence it can conveniently be discharged into a press by means of which any available juice remaining in the material can be extracted. During diffusion, a solvent such as water, or previously extracted juice, or both, is or are admitted to the charge, whilst the juice on reaching the

bottom of the diffuser drains through a filter into a suitable receptacle.

In order that the invention may be fully understood, it will now be further described with reference to the accompanying drawings which show, by way of example, apparatus suitable for the treatment of beetroot for the production of syrup or sugar therefrom.

In these drawings Fig. 1 shows the apparatus partly in side elevation and partly in central vertical section. Fig. 2 is a horizontal section on the line A—A of Fig. 1.

In these drawings the diffuser comprises a sheet metal receptacle 1 made of vertical cylindrical shape and provided with a jacket 1^a of non-conducting material, for example wood. At its lower end the receptacle 1 is provided with a downward extension 2 of inverted truncated shape within which is secured a filter 3 made of perforated sheet metal and of similar shape to the said extension and forming therewith an intermediate annular passage 4 that leads into a receptacle 5 provided with an outlet 5^a. The receptacle 5 is carried by the upper end of a feed cylinder 6 and is secured to the lower end of the downward extension 2 by a coupling sleeve 7. Secured to the lower end of the filter 3 and bearing against the top of the cylinder 6 at 6^a, is a ring 8 of curved shape in section that forms with the receptacle 5, an annular passage 4^a forming a continuation of the annular passage 4. The said ring is provided with inwardly extending pins or projections 9 and ribs 10. 11 is a lift-valve, in the form of a dished metal plate, that is normally seated on the top of the cylinder 6 at 6^a and is capable of being raised to an extent limited by the pins or projections 9, which act as stops, and serve as guides for the valve. This valve normally closes the upper end of the feed cylinder 6 which is in communication with a hopper-like receptacle 12 through a lateral passage 13 controlled by a slide 14. The receptacle 12 serves to hold sliced beet which is fed into the cylinder through the passage 13 when the slide 14 is withdrawn. The beet may be fed through the passage by the aid of a screw conveyor 15 which is so mounted that it can be withdrawn from the passage

to a sufficient extent to enable the slide 14 to be moved into a position to close the communication between the cylinder 6 and receptacle 12 when required. The cylinder 6 is fitted with a piston 16 and is provided at its lower end with a cover 17 formed with a drain passage 18 and spout 19 through which any juice that may leak past the piston can be returned to the diffuser 1, or be otherwise utilized. The slide 14 and piston 16 are operated by hydraulic power as through rams 20 and 21 respectively, working in hydraulic cylinders 20^a and 21^a. The arrangement is such that the slide 14 is first opened to admit of sliced beet being fed to the upper end of the feed cylinder 6 by the aid of the screw conveyor 15 and is then closed, the conveyor being first removed or drawn back, whereupon the feed piston 16 is moved upwards to lift the valve 11 and force the beet through the annular opening formed between the valve and its seat 6^a into the diffuser 1 against the weight of the superposed charge therein. When the piston 16 and slide 14 are operated by, as in the example shown, hydraulic rams, each ram should be made double acting, so that it can be forced both upward and downward.

The diffuser 1 is supplied at or near its upper end with water fed into it through a water heating vessel 22 of any convenient construction provided with a water inlet 23 and a steam inlet 24, which can be adjusted, so that the water will enter the diffuser in a heated condition as desired. 26 is a socket on the vessel 22 in which a thermometer can be placed to determine the temperature of the feed water admitted to the diffuser. The diffuser is maintained at a suitable temperature, as for example by means of a steam or hot water coil 25 of any convenient construction arranged within its non-conducting jacket 1^a and having its inlet and outlet at 25^a and 25^b respectively. At its upper end the diffuser is provided with a hood 27 through which the spent beet is discharged into a press or other receptacle.

The diffuser is furnished at an intermediate part, or at intermediate parts, of its height with one or more valve controlled inlets for the introduction of a solvent such as hot juice or water. Each inlet may have associated therewith means for circulating the juice or water through the beet in the diffuser. In the example shown, there are three inlets with associated means for circulating juice or water in a transverse direction through the beet in the diffuser. In each case the circulating means comprises a pump case 28 with inlet 29 for juice or water, a rotary impeller 30 and chambers 31 and 32 connected to the wall of the diffuser opposite diametrically arranged sets of apertures 33 therein, the said chambers 65 being connected respectively to the inlet and

outlet passages 34 and 35 of the pump case, and the impeller 30 being arranged to be rotated through a spindle 36 and belt driven pulley 37. Each chamber 31 and 32 is provided with a removable cover 38 to admit of its interior being inspected and cleaned. The arrangement is such that juice or water supplied to the inlet 29 through a valve controlled pipe, can be caused by each pump to circulate transversely through the beet in 75 the part of the diffuser opposite the corresponding sets of apertures 33. The inlet 29 will also serve for the introduction of a thermometer to determine the temperature of the juice at the corresponding part of the 80 diffuser.

The solution of sugar extracted from the beet finally passes to the filter 3 through which it flows to the passages 4 and 4^a, receptacle 5 and outlet 5^a to a valve 40 whence it can pass through an outlet 41 to a second valve 42 and thence to a storage receptacle. If desired, the outlet of the valve 42 could be connected to an exhausting device to facilitate the passage of water and juice 90 through the mass of beet or other material under treatment in diffuser 1.

43 is a cylinder connected to the outlet 41 of the valve 40 and to the inlet of the valve 42 and, by a pipe 44 controlled by a valve 95 45, to the bottom of the cylinder 6 and fitted with a piston 43^a adapted to be operated by the plunger of a hydraulic ram 46. The arrangement is such that by closing the valves 42 and 45 whilst leaving the valve 40 open, 100 and raising the piston in the vessel 43 by the hydraulic ram at 46, juice collected in the cylinder 43 can be forced back at any desired intervals through the apertures of the filter 3 for the purpose of clearing these apertures of obstructing matter. The cylinder 43 may be jacketed and heated by steam or hot water to heat the juice and render it more effective for clearing purposes. Also, by closing the valves 40 and 42 and opening 105 the valve 45, and raising the piston 43^a in the cylinder 43, after the cylinder 6 has been charged with beet chips and the slide 14 closed, hot juice or water can be delivered into the lower end of the said cylinder 6 so as to drive out air therefrom before the piston 16 is raised, the air being allowed to escape through one or more valves 6^a which may be hand controlled. Hot juice or water can also be forced into the lower end of the diffuser 1 through the cylinder 6 past the valve 11. Or, hot juice and water can be forced into the lower end of the diffuser 1 through the pipe 41, valve 40 and filter 3, as above described, but not necessarily for cleaning 115 the filter though this will nevertheless take place should the filter be clogged.

The use of apparatus such as described does not change the nature of the several operations necessary for the production of 130

beet sugar as now carried out, but it secures great simplicity in the construction and operation of such apparatus for diffusion in comparison with apparatus at present commonly used, the slow upward movement of the column of beet within the diffuser 1 whilst the stream of solvent water and juice moves slowly in the opposite direction, having the same effect as a battery of many cells 10 charged and emptied in rotation.

The diffuser may be of considerable height, and the force of gravity will then afford sufficient pressure to ensure the efficient flow of its liquid contents.

15 In some instances the slide 14 and piston 16 could be reciprocated automatically and successively and by power other than hydraulic power. The lower end of the beet receptacle 12, may in some cases, be connected to the cylinder 6 by an inclined passage through which the sliced beet can fall by gravity from the receptacle into the cylinder, when the slide 14 is withdrawn, and the screw conveyor 15 dispensed with, but the 20 arrangement shown, in which a screw conveyor is used, is preferred. Also, more than one feed hopper and cylinder and more than one annular filter and lift valve may be provided in connection with a single diffusing 25 chamber. The arrangement described may obviously be also considerably modified in other respects whilst still remaining within the scope of the invention.

What I claim is:—

35 1. Juice extracting apparatus comprising a substantially vertical diffuser, a centrally arranged lift valve located within the lower part of said diffuser and normally closing the lower end thereof and adapted when 40 lifted to form an annular opening between its periphery and the inner surface of said diffuser, means for limiting the upward movement of said valve, a vertical feed cylinder located directly below and connected to the lower end of said diffuser, a receptacle having its lower end connected to the upper end of said feed cylinder by a lateral passage through which solid sliced beet or like material can enter said feed 45 cylinder, means adapted to open and close said passage, a vertically movable piston within said feed cylinder adapted on its upward stroke to lift said valve and force sliced beet or like material, previously admitted to the feed cylinder, into the lower 50 end of said diffuser through the annular opening formed between the lift valve and the inner surface of said diffuser, means for supplying a solvent to an upper part of the diffuser and means for drawing off juice from the lower part of said diffuser.

2. Juice extracting apparatus comprising a substantially vertical diffuser having a truncated lower end portion, a centrally arranged lift valve located within said lower

portion of said diffuser and normally closing the lower end thereof and adapted when lifted to form an annular opening between its periphery and the inner surface of said diffuser and direct material entering the 70 truncated lower portion of said diffuser outward against the inner surface thereof, means for limiting the upward movement of said valve, a feed cylinder connected to the lower portion of said diffuser, means 75 for supplying sliced beet or like material to said feed cylinder, a piston movable within said feed cylinder and adapted on its operative stroke to lift said valve and force the contents of said feed cylinder into the 80 lower end of said diffuser through the annular opening formed between its inner surface and the periphery of the lifted valve and against the inner surface of the lower end portion of the diffuser, means for supplying a solvent to an upper part of the diffuser, means for drawing off juice from the lower part of the diffuser, and means surrounding said diffuser for heating the same 85 and its contents. 90

3. Juice extracting apparatus comprising a substantially vertical diffuser, a centrally arranged lift valve located within the lower part of said diffuser and normally closing the lower end thereof and adapted when 95 lifted to form an annular opening between its periphery and the inner surface of said diffuser, means for limiting the upward movement of said valve, a vertical feed cylinder located directly below and connected to said diffuser, a piston vertically movable in said feed cylinder, a hopper-like feed receptacle having its lower end connected to the upper end of said feed receptacle by a lateral passage, a rotary withdrawable feeding device for forcing sliced material to be treated through said passage from said receptacle into said feed cylinder, a vertically movable slide for opening and closing said passage when said feeding device is sufficiently withdrawn, a reciprocating rod to operate said piston, a reciprocating rod to operate said slide valve, means for supplying a solvent to the upper part of said diffuser and means for drawing off 100 juice from the lower part of said diffuser. 105

4. Juice extracting apparatus comprising a substantially vertical diffuser, a feed cylinder with piston connected to the lower end of said cylinder, a centrally arranged 120 lift valve located within the lower part of said diffuser and normally closing the lower end thereof and adapted when lifted to form between its periphery and the inner surface of said diffuser an annular opening through 125 which material will be forced against the inner surface of the diffuser when the piston makes its operative stroke, and means for causing water or juice to circulate transversely through the diffuser and the con- 130

tents thereof at a part between the top and bottom thereof, said means comprising two chambers having removable covers and arranged at opposite sides of said diffuser and in communication therewith through a plurality of apertures in opposite portions of the wall of said diffuser the inlet for liquid to one chamber and the outlet for liquid from the other chamber extending in the same direction from one side of the diffuser, and a circulating pump comprising a casing fixed to the wall of said diffuser between the said inlet and outlet and having its delivery and suction connection respectively to said inlet and outlet, and a rotary impeller in said casing adapted to cause liquid to circulate continuously, directly and transversely through the contents of the diffuser adjacent to the perforated sides thereof, said casing also having an inlet for the admission of liquid thereto from an external source.

5. Juice extracting apparatus comprising a substantially vertical diffuser, a feed cylinder with piston connected to the lower end 25 of said cylinder, a centrally arranged lift valve located within the lower part of said diffuser and normally closing the lower end thereof and adapted when lifted to form between its periphery and the inner surface 30 of said diffuser an annular opening through which material will be forced against the inner surface of the diffuser when the piston makes its operative stroke, and means for causing water or juice to circulate in a trans- 35 verse direction through the diffuser and its contents at different parts thereof between its top and bottom, said circulating means comprising a plurality of independent pairs of chambers each with an associated circu- 40 lating pump, each pair of chambers having removable covers and being located at opposite sides of and connected to the diffuser and in communication therewith through a plurality of apertures in opposite portions 45 of the wall of the diffuser, and each associated circulating pump being attached to the diffuser and having an inlet for water or juice and its suction and delivery passages directly connected to the associated 50 pair of chambers.

6. Juice extracting apparatus comprising a substantially vertical diffuser, a vertical feed cylinder located directly below the diffuser and central therewith, a centrally arranged lift valve that normally closes the upper end of said feed cylinder, a seating therefor, an annular filter arranged above said lift valve, a piston vertically movable in said feed cylinder and adapted to cause the contents of the feed cylinder to lift said valve and to pass upwards into the diffuser through the annular opening between the lifted valve and its seating, means for supplying a solvent to an upper part of the diffuser, means for drawing off juice from the

lower part of said diffuser through said filter, and means for forcing liquid backward through the filter for the purpose of cleaning the same.

7. Juice extracting apparatus comprising 70
a substantially vertical diffuser, a feed cylinder located below the diffuser, a centrally arranged lift valve that is located within and normally closes the lower end of said diffuser, a filter within said diffuser and 75
above said valve, a piston vertically movable in said feed cylinder and adapted to cause the contents of the feed cylinder to lift said valve and to pass upwards into the diffuser through the annular opening 80
between the lifted valve and diffuser, means for supplying a solvent to an upper part of the diffuser, a conduit for drawing off juice from the lower end of said diffuser through said filter and provided with two controlling valves, a juice transfer cylinder connected at one end to said conduit at a part thereof between its two valves and adapted to receive juice from said diffuser and a piston within said cylinder adapted to 85
force juice from said cylinder back into the diffuser through said filter. 90

8. Juice extracting apparatus comprising a substantially vertical diffuser, a feed cylinder located below said diffuser, a centrally arranged lift valve arranged within and normally closing the bottom of said diffuser, means for limiting the upward movement of said valve, a piston movable in said feed cylinder and adapted to cause the contents thereof to lift said valve and to pass upward into the diffuser through the annular opening between the diffuser and valve, a valve controlled air outlet at the upper part of said feed cylinder, means for supply a solvent to an upper part of the diffuser, a juice transfer cylinder adapted to be connected at one end to the lower end of the diffuser and to the lower end of the feed cylinder and valve means controlling each connection whereby juice can be fed into the transfer cylinder from the diffuser and afterwards be forced into the feed cylinder for the purpose set forth.

9. Juice extracting apparatus comprising 115
a substantially vertical diffuser, a filter within
the lower end of said diffuser, a vertical
feed cylinder located directly below the
diffuser and having a valve controlled air
outlet near its upper end, a centrally ar- 120
ranged lift valve adapted normally to close
the communication between said diffuser
and the upper end of said feed cylinder, a
piston vertically movable in said feed cyl- 125
inder and adapted to cause the contents
thereof to lift the valve and enter the dif-
fuser between the lower end thereof and
said valve, means for supplying a solvent
to an upper part of the diffuser, a conduit
provided with two control valves for draw- 130

ing off juice from the bottom of said diffuser through said filter, a juice transfer cylinder connected at one end to said conduit between the valves therein, a separate valve controlled pipe connecting the same end of the juice transfer cylinder to the lower end of the feed cylinder and a piston for forcing juice from said transfer cylinder to the lower end of said diffuser or to the lower end of said feed cylinder, at will, and according to the position of the said control valves.

Signed at Bembridge, in the Isle of Wight, aforesaid, this thirtieth day of May, 1918.

JOHN ISAAC THORNYCROFT.
